UNITED STATES PATENT OFFICE.

ELMER E. RICE, OF EAU CLAIRE, WISCONSIN.

HINGE.

No. 864,690.

Specification of Letters Patent.

Patented Aug. 27, 1907.

Application filed January 4, 1907. Serial No. 350,780.

To all whom it may concern:

Be it known that I, ELMER E. RICE, a citizen of the United States, residing at Eau Claire, in the county of Eau Claire and State of Wisconsin, have invented 5 certain new and useful Improvements in Hinges, of which the following is a specification, reference being had therein to the accompanying drawing.

This invention relates to improvements in detachable hinges and consists in the novel construction, 10 combination and arrangement of parts hereinafter described and claimed.

The object of the invention is to provide a simple, strong, durable and inexpensive hinge of this character for removably or detachably mounting screen 15 doors, the covers or lids of sample cases, and similar swinging devices.

Further objects and advantages of the invention, as well as the structural features by means of which they are attained, will be made clear by an examination of 20 the specification, taken in connection with the accompanying drawings, in which the same reference numerals indicate corresponding portions throughout, and in which,

Figure 1 is a perspective view of the improved detachable hinge, looking at its inner side; Fig. 2 is a similar view of the attaching plate or stationary section of the two-part member of the hinge; Fig. 3 is a perspective view of a hinge with the attaching plate removed; Fig. 4 is a horizontal or cross section taken 30 on the plane indicated by the line 4—4 in Fig. 1; Fig. 5 is a perspective view of a slightly modified form of the hinge; and Fig. 6 is a cross section through the same.

Referring more particularly to Figs. 1 to 4, inclusive, of the drawings, the numerals 1 and 2 denote the two members or leaves of the improved hinge, the former of which is single and the latter of which is double or composed of two separable or detachable sections 3, 4. The member 1 is adapted to be secured 40 on a door or the like by screws or similar fastenings inserted in countersunk openings 5 formed in it; and it is pivoted to the section 3 of the member 2, preferably by a pintle 6 passed through alining sockets 7 formed on said members. The section or plate 4 serves as an attaching plate and may be termed the 45 stationary section since it is secured upon the door frame or the like by screws inserted in countersunk openings 8 formed in said plate. In this plate are also formed one or more keeper openings 9 for the reception of projections 10 provided upon the plate or section 3. As here shown, the projections 10 are in the form of loops stamped out from the plate 3. These loops, when inserted in the keeper openings 9 are adapted to fit over upwardly projecting tongues 11 55 formed in the openings 9. These tongues 10 are

formed by making the openings 9 of inverted U-shape and by recessing or cutting away the rear faces of the portion of the plate between the vertical arms or branches 12 of the openings 9, into which arms or branches the ends of the loops 10 drop as the tongues 60 or projections 10 enter said loops. In attaching the plate 3 to the plate 4, the former is placed against the outer face of the latter, so that the loops 10 enter the large upper portions of the openings 9, and said plate is then dropped or moved downwardly so that the 65 loops 10 drop over the projections or tongues 11, as shown in Fig. 1.

Instead of employing two loops and tongues, as shown in Fig. 1, I may provide but a single tongue 13 and a single loop 14, as shown in Figs. 5 and 6. The 70 loop 14 is arranged centrally upon the plate 3 and the tongue 13 is tapered upwardly and arranged in the center of a centrally-disposed opening 15 formed in the plate 4. The opening 15 is of gradually increasing width from its bottom to its top, as shown. 75

From the foregoing, it will be seen that a hinge when constructed in accordance with the invention may be made at a comparatively small cost and that its two detachable sections may be quickly and easily engaged and disengaged, so that the door or other 80 swinging object which it supports may be applied to and removed from its frame without the necessity of removing any screws or similar fastenings.

Having thus described my invention, what I claim as new and desire to secure by Letters Patent of the 85 United States, is:—

1. A hinge comprising pivotally connected members, one of said members consisting of two flat plates, a tongue upon one of said plates, and a loop upon the other of said plates adapted to engage said tongue. 90

2. A detachable hinge comprising pivotally connected members, one of said members consisting of two flat plates, one of said plates being apertured and recessed to form a tongue lying wholly within the plane of said plate, and the other of said plates having a loop stamped outwardly from 95 it for engagement with said tongue.

3. A detachable hinge comprising pivotally connected members, one member consisting of two flat plates, one of said plates having a substantially U-shaped opening, and a tongue in said opening, the rear face of said tongue being recessed, and the other of said plates having a substantially U-shaped loop stamped out from it and adapted to enter said opening and to surround said tongue, the ends of said loop being located in the ends of said openings, and the central portion of said loop being located in the recessed portion of said tongue and lying within the plane of the inner face of the first-mentioned plate, substantially as shown and described. 100

In testimony whereof I hereunto affix my signature in presence of two witnesses.

ELMER E. RICE.
